PROCESS FOR RENOVATING OR RESHARPENING RECORDING STYLI

Charles F. Strandberg, Greensboro, N. C.

Application January 18, 1950, Serial No. 139,239

4 Claims. (Cl. 134—42)

1

The invention relates to a process for renovating or resharpening recording styli.

Sapphires are at present widely used as styli for recording on aluminum base records or disks. Such styli are quite expensive and in accordance with the present practice must be frequently replaced or resharpened to avoid the production of unpleasant sounds which are frequently referred to as hissing, squealing, scratching and the like. The resharpening of such styli as at present practiced is an expensive and unsatisfactory procedure which results in serious wear on the tip.

It has been generally considered that these unpleasant noises are due to wear, breakage or chipping of the styli by reason of their contact with the aluminum base portion of the recording disks. Contrary to the accepted view I have found that in most cases where these undesirable noises occur the sapphire itself, which is a very hard stone having a hardness approaching that of the diamond, has not been permanently impaired, but instead has become coated with or has its point embedded in tiny pieces of aluminum collected from the base. It is these tiny pieces of irregularly shaped aluminum which in the vast majority of cases result in defective styli and produce extreme levels of noises in instantaneous disk recording. Normally the record groove wall is polished by burnishing facets, which are extremely narrow, having a maximum width of about 0.001 inch, and which extend far beyond that portion of the sapphire which is functional, namely the tip, and which portion actually makes the groove.

By removing the aluminum particles from a used sapphire stylus I have found that contrary to previous views prevailing in the industry the sapphire itself was undamaged and the stylus restored, renovated or sharpened so that it could again be used for recording purposes without the production of unpleasant sounds. Attempts have been made to mechanically or physically remove the aluminum particles, as, for example, by the use of a cloth having the proper abrasive characteristics and of sufficient softness so as to remove the aluminum without damaging the sapphire. While these efforts have been successful, in that it is possible to remove the aluminum particles and thus restore the usefulness of the styli, nevertheless the mechanical or physical cleaning of the stylus has been found to be relatively inefficient, and in accordance with my invention chemical cleaning is employed, which treatment has proved to be very successful in actual practice.

Various reagents may be employed, including

2

suitable acids, bases and salts for dissolving the aluminum, and as examples hydrochloric acid, sodium hydroxide, potassium hydroxide, sodium carbonate, and potassium carbonate may be mentioned by way of illustration rather than by way of limitation. The strength of these reagents may be varied widely without departing from my invention, and reagents of any strength capable of dissolving the aluminum may be employed. As a specific example, sodium hydroxide of 40% concentration has been successfully employed. The reagent may be arbitrarily colored red for easy identification.

In order to simplify and standardize the chemical treatment of the sapphire styli I have devised an improved apparatus whereby the degree of immersion of the stylus into the reagent may be regulated, so as to permit dipping the sapphire portion of the stylus in the reagent while preventing contact of the reagent with the shank or stem of the stylus, which latter portion is generally formed of brass or aluminum or other metal which would be damaged by contact with the cleaning reagent. A suitable device for accomplishing this purpose is disclosed in the accompanying drawings, in which

Fig. 1 is a side elevation showing a sapphire tip cleaning instrument embodying my invention;

Fig. 2 is a plan view on a smaller scale than Fig. 1 showing the base or pedestal which supports the cleaning instrument; and

Fig. 3 is a vertical section on a larger scale than Fig. 1 showing the stylus holding chuck of the cleaning instrument, with a stylus supported therein.

Referring to the drawings, 10 denotes a wooden pedestal or block having a central depression or well 11 therein, in which the bottom of a reagent containing tube or vial 12 is seated. The vial is preferably of transparent material, such as glass, plastic or the like, and may be provided with a suitable stopper 13 of rubber or the like having a central passage 14 extending therethrough, through which may be passed a stem 15 threaded through a substantial portion of its length and carrying at its lower end a stylus holding chuck 16 preferably formed of plastic material, such as polystyrene. A pair of nuts 17 and 18 are provided at the top and bottom of the rubber stopper 13, said nuts having internal threads coacting with the threads of the chuck holding stem, and permitting the same to be raised or lowered by rotation of a suitable wing nut or the like 19 secured at the top of the stem 15.

The polystyrene chuck 16 is provided with an

axial socket 20 extending upwardly therethrough, which socket may be lined with rubber cushioning material to yieldingly hold a stylus shank 21, the tip 22 of which projects beyond the socket. It will be obvious that the metal shank of the stylus will be protected from the reagent in the vial 12 by reason of its insertion into the socket 20, although normally the lower end of the chuck will not extend materially below the surface of the reagent liquor.

If desired a diametrical saw cut may be provided at the lower end of the chuck intersecting the socket 20 in order to augment the gripping action of the socket on the stylus shank.

In operation the vial 12 may be filled to any desired level with a suitable stylus tip cleansing reagent, such as 40% sodium hydroxide. The stem of the stylus to be cleaned is fitted into the socket 20 in the chuck 16 and the stopper 13 carrying the stem 15 with the chuck 16 at the lower end thereof is then inserted in the neck of the vial and the position of the chuck 16 adjusted by turning the wing nut 19 until the stylus tip to be cleaned is immersed in the cleaning fluid and the lower end of the chuck preferably just touches the surface of the cleaning reagent. The chuck 16 is unaffected by the reagent in the vial owing to the nature of the material of which it is formed and the stylus stem, which may be of metal, is protected within the socket 20 from contact with the reagent. The stylus tip remains immersed in the cleaning fluid within the vial until such time as the aluminum adhering to the stylus tip is dissolved by the reagent, whereupon the stopper 13 carrying with it the stem 15, chuck 16 and the renovated or resharpened stylus is withdrawn from the mouth of the vial and the stylus removed from the chuck. The resharpened stylus is then ready for renewed use.

The invention has been described in detail for the purpose of illustration, but it will be obvious that many variations and modifications may be resorted to without departing from the spirit of the invention. Thus, while in the foregoing description sapphire styli have been referred to, the invention in its broadest aspects is applicable to the renovating or resharpening of other types of styli the tips of which may have become dull by reason of the presence thereon of particles of soft metal, such as aluminum, on account of contact between such styli tips and the metal base portions of the recording disks.

In addition to the well 11 in which the vial 12 is seated the pedestal or block 10 may be provided

with an additional well 11' to receive a slightly smaller vial 12' in which the reagent is originally supplied and from which the desired quantity of the reagent may be poured into the larger vial 12.

I claim:

1. A method of resharpening the sapphire tips of recording styli which have become dull by reason of the adherence to said tips of portions of aluminum gathered from contact with the base portions of recording disks or the like, which comprises chemically removing the adhering aluminum particles from the tips by application to the tip of a chemical which is reactive with the aluminum portions but is non-reactive with sapphire.

2. A method of resharpening the sapphire tips of recording styli which have become dull by reason of the adherence to said tips of portions of aluminum gathered from contact with the base portions of recording disks or the like, which comprises chemically removing the adhering aluminum particles from the tips by immersion in a chemical bath reactive with the aluminum particles but non-reactive with sapphire.

3. A method of resharpening the sapphire tips of recording styli which have become dull by reason of the adherence of said tips of portions of aluminum gathered from contact with the base portions of recording disks or the like, which comprises chemically removing the adhering aluminum particles from the tips by immersion in a bath of sodium hydroxide.

4. A method of resharpening the sapphire tips of recording styli which have become dull by reason of the adherence to said tips of portions of aluminum gathered from contact with the base portions of recording disks or the like, which comprises chemically removing the adhering aluminum particles from the tips by immersion in a chemical bath reactive with the aluminum particles but non-reactive with sapphire and regulating the degree of immersion.

CHARLES F. STRANDBERG.
